US0D1001655S

(12) **United States Design Patent** (10) Patent No.: **US D1,001,655 S**
(45) Date of Patent: ** Oct. 17, 2023

(54) **MEASURING INSTRUMENT**

(71) Applicant: **TLV CO., LTD.**, Hyogo (JP)
(72) Inventors: **Mamoru Nagase**, Hyogo (JP); **Akira Oizumi**, Hyogo (JP); **Masashi Matsumoto**, Hyogo (JP); **Eiji Takenaka**, Hyogo (JP); **Hiroshi Shiromoto**, Hyogo (JP)
(73) Assignee: **TLV CO., LTD.**, Kakogawa (JP)
(**) Term: **15 Years**
(21) Appl. No.: **35/513,913**
(22) Filed: **Sep. 30, 2021**

(80) **Hague Agreement Data**

Int. Filing Date: **Sep. 30, 2021**
Int. Reg. No.: **DM/217000**
Int. Reg. Date: **Sep. 30, 2021**
Int. Reg. Pub. Date: **Apr. 1, 2022**

CLAIM

The ornamental design for a measuring instrument, as shown and described.

DESCRIPTION

1. Measuring instrument

1.1 : Perspective

1.2 : Front

1.3 : Back

1.4 : Top

1.5 : Bottom

1.6 : Left

1.7 : Right

1.8 : Back perspective view

The broken lines shown in the drawings illustrate portions of the article that form no part of the claimed design.

1 Claim, 8 Drawing Sheets
